UNITED STATES PATENT OFFICE.

DAVID R. PROCTOR, OF CHICAGO, ILLINOIS, ASSIGNOR, BY DIRECT AND MESNE ASSIGNMENTS, TO THE GLOBE SECTIONAL HEAD COMPANY, OF SAME PLACE.

BARREL-HEAD.

SPECIFICATION forming part of Letters Patent No. 392,570, dated November 6, 1888.

Application filed March 12, 1888. Serial No. 267,049. (Model.)

To all whom it may concern:

Be it known that I, DAVID R. PROCTOR, of Chicago, county of Cook, and State of Illinois, have invented certain Improvements in Barrels, of which the following is a specification.

My invention relates to the construction of a barrel-head and the arrangement of its parts in such a manner that the head can be removed and then replaced again without removing or disturbing the hoops upon the barrel, and doing this in a cheap, expeditious, and secure manner.

My said invention will be hereinafter more fully described with reference to the accompanying drawings, in which—

Figure 1 represents a perspective of a portion of a barrel with a head in it embracing in its construction and arrangement of parts my said improvement; Fig. 2, a like view of the head of a barrel, the parts being detached in order to display the construction of the same; Fig. 3, a transverse vertical section of the two principal sections B and C of the head and the two keys D and E in position, made as indicated by the broken line x x in Fig. 1; Figs. 4 and 5, detail views in perspective of the keys D and E; and Figs. 6 and 7, detail views of parts, all the detail views, including Fig. 3, on an enlarged scale.

The principal sections B and C of the head are each of the same forms and dimensions. Their inner edges are cut away, so as to form V-shaped grooves, into which fit snugly corresponding formations on the side edges of keys D and E, as shown in Fig. 3. They are also cut away on their faces, so as to form ledges b and c on their upper sides at one end and other exactly similar ledges, b' c', on their other ends on their under sides, as shown by the broken lines in Fig. 2. These ledges, being triangular in their surface, form and are designed to afford proper bearing-surfaces for the wide ends or butts of the keys.

The keys D and E have exactly the same form and dimensions. Their outer ends are beveled to fit into the grooves in the staves made by the croze just as the principal sections of the head are. The upper surface of the key E is cut away from its butt or wide end

back to within a few inches of its narrow end, 50 where it is left with its full thickness, as shown at e^2 in Fig. 4, in order that it may stand out flush with the head-sections, and thus have its full form and strength preserved at that end. The under surface of the key D is cut away in 55 a manner that is exactly similar for the same purpose, as shown in Fig. 5, and each has its side edges cut away correspondingly in order to form tongues d^3 and e^3 , to fit snugly within the grooves in the side edges of the head-sections B and C, and to form shoulders d^4 and e^4 to rest against the head-sections, as hereinbefore specified. The butts or broad ends of the keys overlap each other lengthwise for a few inches and still leave spaces long enough 60 as well as wide enough above and below each key for all requisite endwise motion of each when forced in or out of position for the purpose of closing or opening the head.

The endwise lap of the butts of the two keys 70 is long enough to make the joints between the two parts fluid-tight, especially when they are drawn together by the screw F. The joints thus made between the side edges of the head-sections and the side edges of the keys are especially tight and strong, because in addition 75 to the tongue-and-groove construction hereinbefore specified the edges of the keys—i. e., the shoulders d^4 e^4 —extend over and fit down upon the upper and lower surfaces, respectively, of 80 the two head-sections; and, moreover, the tongue-and-groove formations can be forced into close contact by reason of the wedge-like form of the keys and their being capable of being driven, by blows against their butt-ends 85 as well as their outer ends, fully home into the croze.

In Fig. 1 the barrel is shown as closed, and a screw, F, which extends through key D down into key E, is used to prevent the two keys 90 having lengthwise motion upon each other in case of any jars or strains upon the side ends of the barrel. In order to open the head, that screw must be removed, and by any suitable tool inserted in the hole d the key D can be 95 forced endwise from the croze, and then the key E is removed in a similar manner. The head-sections can then be easily taken out.

To close it again, the key E is driven into position between the head-sections, and then the key D likewise, and then the screw F is turned in.

5 By reason of the facility with which this improved head can be opened and closed and the tightness of all the joints made between the keys themselves and between them and the head-sections, wasting and smearing of 10 the contents of the barrel are effectually prevented in case the barrel should contain pickle, sirup, or oil, which would be uncleanly and offensive.

15 What I claim as my invention, and desire to secure by Letters Patent, is—

1. A barrel-head composed of sections having grooves in their inner edges and two keys, D and E, the edges of which incline from their inner to their outer ends and present, when 2c their butts are overlapped, tongue formations to correspond with the grooves in the head-sections, and are capable of being driven end-wise from their butts to make tight joints with the sections and with the croze in the staves

at their narrow ends, substantially as described.

2. The described head-sections B and C, cut away to form ledges *b* and *c* in their upper sides at one end and on their lower sides at the other end, in combination with the keys 30 D and E, the upper and lower surfaces, respectively, being cut down from their butts to near their small ends, on which are left the parts *e*² and *d*², of full thickness, adapted to secure strength at their narrow ends and 35 play-room for endwise motion of the keys upon each other, substantially as described.

3. In combination with the described keys D and E, the butts of which are overlapped one upon the other, the screw-hole *d*² through 40 both keys, and the screw F, adapted to lock together and unlock the butts, substantially as described.

DAVID R. PROCTOR.
